(57) **CLAIM**

What is claimed is the ornamental design for a vertical digital projector, as shown and described herein.

DESCRIPTION

FIG. 1 is an elevated, perspective view of an embodiment of a vertical digital projector in accordance with the present invention;

FIG. 2 is a front view thereof;

FIG. 3 is a rear view thereof;

FIG. 4 is a top view thereof;

FIG. 5 is a right side elevation view thereof;

FIG. 6 is a left side elevation view thereof; and,

FIG. 7 is a bottom view thereof.

The broken lines are shown to illustrate the environment only and form no part of the claimed design.
